UNITED STATES PATENT OFFICE.

OLIVER J. ROSSELOT, OF KOKOMO, INDIANA.

BURNER FOR HEATING STOVES.

1,389,990.

Specification of Letters Patent. Patented Sept. 6, 1921.

Application filed March 30, 1920. Serial No. 369,877.

To all whom it may concern:

Be it known that I, OLIVER J. ROSSELOT, a citizen of the United States, residing at Kokomo, in the county of Howard and State of Indiana, have invented certain new and useful Improvements in Burners for Heating Stoves, of which the following is a specification.

This invention relates to an oil or gas burner, and while it may be utilized for any suitable purpose, it is especially designed for use in connection with heating stoves.

The main object of this invention is to provide a simple, economical, durable and efficient burner to be used for heating purposes.

Another object of the invention is to so construct the burner that it is self generating; nonwarppable, and will furnish substantially perfect combustion at either a low or high fire.

A further object of the invention is to provide a flame spreader in connection with the burner, the said spreader being lined with asbestos on its under side, and so constructed that it serves a tri-fold purpose, namely; as a spreader for the flame; to protect the bottom portion of the burner, and being lined with asbestos it acts as a self lighter for the burner.

The foregoing and such other objects as may appear from the ensuing description are attained by the construction, combination, arrangement and location of the parts hereinafter more fully described, such as illustrated by the accompanying drawings, and particularly pointed out in the claims appended hereto, it being understood that slight changes in the precise construction, proportions and minor details may be resorted to without departing from the spirit or sacrificing any of the advantages of the invention.

In the accompanying drawings forming a part of this specification it will be seen that:—

Figure 1, is a central sectional elevation of a heating stove with the improved burner embodying my invention shown therein, and showing in outside elevation of the pipe

connections broken away in parts, and a portion of the oil tank.

Fig. 2, is a transverse sectional view taken through the burner on the lines 2—2, Fig. 1, looking in the direction of the arrow, and

Fig. 3, is an inverted plan of the spreading plate detached from the burner.

Similar numerals of reference are employed to designate like parts throughout the several views of the drawings.

In carrying out my invention, as shown in Fig. 1, the numeral 1 indicates the outer casing of a heating stove of any suitable or desirable construction, and 2 is the base portion of said stove. The numeral 3 designates the oil or fuel tank which is preferably located about four feet higher than the burner, in order to furnish the proper fuel feeding pressure to the burner, said tank being connected with the burner by the feed piping 4, provided with a suitable stop valve 5, and a fuel supply regulating valve 6, said piping 4 being fixedly connected to the interiorly threaded inlet portion 7 formed at the bottom portion of the burner 8, which is mounted in any suitable or desirable manner within the casing 1, at the base portion thereof, the main body portion of the said burner consisting of a single casting formed with an upper arch-shaped member 9, a vertical wall 10 at each side thereof, and a central inner arch-shaped inner wall 11 provided with a downwardly extended outlet opening 12 formed through its upper central arched portion. At each side of the central inner wall 11 is formed an opening 13 for the admission of a volume of air into the arch-shaped air trunk or chamber 14, the said burner being formed with a circular base member 15 provided with a series of different size orifices 16, 17 and 18 therethrough at each side of its central portion and arranged in a semi-circle for the purpose hereinafter described. Formed within the base member is a horizontal fuel feeding duct 19 which communicates with a vertical feeding duct 20 formed in the right hand wall of the burner, said duct 20 in turn communicating with a horizontally positioned duct 21 leading from the right hand wall of the burner

to the central portion thereof, and provided with a downwardly extending outlet 21' for the discharge of the fuel. Arranged centrally of the burner 8 between its inner wall 11 is a flame spreader plate 22, which is supported upon the upper surface of the circular base member 15, and suitably secured thereto by a plurality of pins 23, which pass through the openings 24 and fitted into corresponding openings formed in the base member. The flame spreader plate 22 is formed with a recessed lower surface 25 for the reception of the asbestos wicking which is coiled within the recessed portion of the said plate in convolute form with each of its terminal end portions passing through an orifice 26 formed through the said plate, the other orifices 26 being also filled or plugged with asbestos wicking.

From the foregoing description taken in connection with the accompanying drawings, it will be readily perceived that the oil is first fed through the pipe 4 into the horizontal duct 19, from thence into the vertical duct 20, thence into the horizontal duct 21, from whence it is discharged through the outlet 21' into contact with the flame spreader plate 22, and as the oil is discharged from the outlet 21' it comes into contact with a volume of air which is passing through the outlet 12 formed through the wall 11, thus creating a downward blast of commingled air and oil, thereby producing a fuel vapor which becomes ignited over the flame spreader plate 22, and produces an intense heat.

When the burner is first lighted the oil burns on the spreader plate without emitting smoke or odor until the burner is hot, and as the feed of the oil is increased the flame spreads and burns through the orifices 16, 17 and 18, thus forming a solid blaze substantially over the entire circle of the burner.

It will be obvious that the volume of air flowing into the arched air chamber prevents the arch member from warping, while the orifices 16, 17 and 18 formed through the circular base member serve to prevent said base member from warping, and the flame spreader plate being lined with asbestos wicking, and the openings therethrough being filled with said wicking it serves to fully protect the base member of the burner and at the same time the asbestos wicking acts as a self lighter for the burner.

The burner is so constructed that there are no parts likely to get out of order, and the feeding ducts may be readily cleaned by removing the screw-threaded plugs 27 fitted within the threaded openings formed through portions of the burner walls.

It will be understood that it takes from three to five minutes for the gas to generate;

that these burners are made of varying sizes; 65 that the orifices 16, 17 and 18 are formed through the circular base member to correspond with the different size burners, and the burner may be utilized as a gas burner as well as an oil burner.

Having thus described my invention, what I claim and desire to secure by Letters Patent is:—

1. A burner for heating stoves comprising a single casting formed with a circular base having a series of openings of varying sizes therethrough and a horizontal fuel duct formed therein, a vertical wall formed at each end thereof, one of said walls having a vertical fuel feeding duct formed therein, a horizontal fuel feeding duct secured within said casting, said ducts communicating with each other, an arched shaped air chamber formed by and within the casting, a downwardly extended fuel feeding outlet within 85 said air chamber, and air outlet formed in the center of the arch for the discharge of the commingled air and fuel.

2. A burner for heating stoves comprising a single casting formed with an extended 90 circular base member and a horizontal fuel duct formed within said base member, a vertical wall formed at each end thereof, one of said walls having a vertical fuel feeding duct formed therein, an upper horizontal 95 fuel feeding duct secured to one of said walls within the casting, said ducts communicating with each other, an arched shaped air chamber formed by and within the casting, a downwardly extended fuel feeding outlet 100 within said air chamber, an outlet in the center of the arch for the discharge of the commingled air and fuel, and a flame spreader secured to the upper surface of said base member.

3. A burner for heating stoves comprising a single casting formed with an extended circular base member, an upper arched member with hollow side walls forming an arch-shaped air chamber within the casting, a horizontal feed duct formed within the base member, a vertical fuel feed duct formed in one of the side walls, an upper horizontal fuel feed duct within the casting, said ducts communicating with each other, a flame spreader plate recessed within its lower face and having a plurality of orifices therethrough, a convolute asbestos wick arranged within the recessed portion of said plate and filling the said orifices, and an outlet formed in the center of the arch for the discharge of the commingled air and fuel against said spreader plate.

4. A burner for heating stoves comprising a single casting formed with a horizontal fuel feed duct within the base portion thereof, a vertical fuel feed duct formed in one of its side walls, an upper horizontal fuel feed

duct within the casting, an arch-shaped air chamber formed within the casting, an extended circular base member, a flame spreader plate secured to the upper face of the base member having a recessed lower face and a plurality of orifices therethrough, a convolute asbestos wicking arranged within the recessed portion of said plate and filling

the said orifices, a series of openings of varying sizes formed through said base member 10 and arranged in a semi-circle at each side of the spreader plate, and an outlet formed in the center of the arch for the discharge of the commingled air and fuel against said spreader plate.

OLIVER J. ROSSELOT.
